UNITED STATES PATENT OFFICE.

JOHN HENRY ORFEUR, OF STOWMARKET, ENGLAND.

APPARATUS FOR MENDING AND CLEANING SACKS.

SPECIFICATION forming part of Letters Patent No. 594,963, dated December 7, 1897.

Application filed June 14, 1897. Serial No. 640,793. (No model.) Patented in England July 2, 1895, No. 12,783.

To all whom it may concern:

Be it known that I, JOHN HENRY ORFEUR, a subject of the Queen of Great Britain and Ireland, residing at Milton Road, Stowmarket, in the county of Suffolk, England, have invented a certain new and useful Improved Apparatus for Use in Mending and Cleaning Sacks and the Like, (for which I have obtained a patent in Great Britain, No. 12,783, dated 10 July 2, 1895,) of which the following is a specification.

The object of my invention is to provide a convenient apparatus for holding flour and other sacks and the like while being cleaned 15 or repaired.

Referring to the drawings which form a part of this specification, Figure 1 is a general plan of the apparatus, and Fig. 2 a longitudinal section of a portion of it.

Upon suitable A-shaped or other standards *a* I mount a hollow shaft *b*, having therein a longitudinal slot or opening *c*. Inside this hollow shaft *b* is a spindle *d*, capable of being moved longitudinally by a lever *e*, one 20 end of which is pivoted to a frame *f*, the pivoting-point *g* being outside the axis of the shaft *b*. The other end of *e* moves along a segmental rack *h* and has a spring-catch *i*, by which *e* may be kept at any required position 25 along *h*. On the hollow shaft *b* is a sliding collar *j*, to which is attached the pin *k*, passing through the slot *c* and then attached to a block *l* at the end of spindle *d*. The collar *j* is grooved to accommodate a friction roller 30 or collar *m*, furnished with the stud *n*, which passes freely through the lever *e*. One end of spindle *d* is surrounded by the tubular sleeve *o*, between one end of which and the block *l* is the spiral spring *p*. Through spindle *d* is placed a stop-pin *q* or an equivalent. 35 To the end of shaft *b* which extends beyond the end of one of the bearings of one of the supports *a* is fastened a rectangular frame or table *r*, of greater length than breadth, the spindle *d* extending along the middle of it and being kept central by passing through cross-bars *s*, connecting the opposite sides of frame *r*. To spindle *d* is attached the eared lug *t*, and to sleeve *o* the eared lug *t'*, and to 40 lugs *t* and *t'* are pivoted slotted arms *u* and *u'*, whose slotted ends pass through the sides of frame *r*, pins *v* passing through frame *r* and

also through the slots *w* in the arms *u u'*. To the outer ends of *u u'* are pivoted battens *x*, parallel with the sides of frame *r* and having the ends *y* returning toward the center of the end of the frame *r*. The width of frame *r* and battens *x*, when close together, is to be such as to admit of the sack or the like being easily drawn over them. At the center of the 55 end frame *r* nearest the hollow shaft *b* I fix upstanding pins or points *z*, one on each side of the frame, and these pins may be made to remove as and when required.

In assembling the parts together in the first 60 instance I arrange that when the lever *e* is at the extreme outer end of the rack *h* the side battens *x* are close to the frame *r*, as shown in full lines in the drawings.

The action of the apparatus is as follows: 65 The frame *r* and the side battens *x* are inserted in the mouth of the sack or like, which is then drawn to the rack end of the apparatus, and the mouth ends of the sides of the sack or the like may be passed over the pins 70 or points *z* to prevent cross-puckering. The lever *e* is then drawn toward the frame *r*, as shown in dotted lines, whereupon the battens *x* will be moved away from the frame or table *r* and so distend the sack or the like, which 75 may then be cleaned first on one side and then on the other by turning over the frame *r*. The center of *r* may be paneled on one or both sides. A hand-wheel and screw may be provided at the top of the bearing carrying 80 the end of shaft *b* nearest the frame *r* for the purpose of retaining the tubular shaft *b* in position when the required side of frame *r* is uppermost. When the lever *e* has been 85 brought over by usual force, it can be moved a little farther by applying greater pressure, so as to overcome the spring *p*. This causes the extreme arms *u* to be pushed out to a greater extent than arms *u'*, the stop-pin *q* preventing the spring *p* drawing spindle *d* 90 back too far.

The machine can be used for repairing as well as cleaning sacks or the like.

The various parts of the apparatus may be of appropriate and convenient materials, the 100 standards *a*, spindle *d*, lever *e*, rack *h*, and arms *u u'* being of metal, for instance, and frame *r* and battens *x* of wood, and the various parts are capable of variation in form

without departure from the spirit of the invention.

Having now described my invention, what I claim as new, and desire to secure by Letters Patent, is—

The apparatus consisting essentially of a frame the width of which can be varied so as to accommodate itself to and retain thereon a sack or the like, the said apparatus comprising the standards *a*, the tubular shaft *b*, provided with the slot *c*, the spindle *d*, the lever *e*, the frame *f*, the rack *h*, the spring-
catch *i*, the collar *j*, the pin *k*, the block *l*, the

roller *m*, the stud *n*, the tubular sleeve *o*, the spiral spring *p*, the table *r*, the cross-bars *s*, the eared lugs *t* and *t'*, the arms *u* and *u'*, provided with the slots *w*, the battens *x*, the return ends *y*, and the pins *z*, the whole substantially as described and illustrated.

In witness whereof I have hereunto set my hand in the presence of two witnesses.

JOHN HENRY ORFEUR.
